UNITED STATES PATENT OFFICE.

CARL H. BISSELL, OF SYRACUSE, NEW YORK, ASSIGNOR TO CROUSE-HINDS COMPANY, OF SYRACUSE, NEW YORK, A CORPORATION OF NEW YORK.

DESIGN FOR AN ELECTRICAL LAMP.

Application filed June 20, 1923. Serial No. 6,537. Term of patent 3½ years.

To all whom it may concern:

Be it known that I, CARL H. BISSELL, a citizen of the United States, resident of Syracuse, county of Onondaga, State of New York, have invented a new, original, and ornamental Design for Electrical Lamps, of which the following is a specification, reference being had to the accompanying drawing, which is a perspective view of

an electrical lamp, showing my new design.

I claim:

The ornamental design for an electrical lamp, substantially as shown.

In testimony whereof, I have hereunto signed my name, at Syracuse, in the county of Onondaga, and State of New York, this 25th day of May, 1923.

CARL H. BISSELL.
